HOSEA H. HUNTERY'S. DESIGN FOR COOKING STOVE
ASSIGNOR TO. DAVID T. WOODROW

Hosea H. Huntley of Cincinnati Ohio
a citizen of
David P. Woodrow of same place.
Letters Patent No 456 Dated May 11. 1852.

The schedule referred to in these Letters Patent and making part of the same

To all whom it may concern.

Be it known that I Hosea H. Huntley of the City of Cincinnati in the County of Hamilton and State of Ohio have invented or produced a new and original design for a Cooking Stove and I do hereby declare that the following is a full and exact description of the same reference being had to the accompanying drawings and to the Figures and Letters of reference marked theron.

Similar Figures and Letters refer to corresponding parts of the produced design.

Fig 1 is a back elevation of the stove resting on its feet showing the back plate (B.B) in connection with the bottom and top plates.

Fig 2 is a front elevation of the stove resting on its feet and representing the edges of the top and bottom plates together with an edge view of the Hearth plate.

Fig 3 is a side elevation of the stove resting on its feet showing the edges of the top, bottom, front and back plates &c. Fig 4 is a view of the top plate in connection with the Hearth as may be seen by looking down on the stove when put together

Figures 5, 6 and 7 are sectional views of the various mouldings belonging to the stove &c.

The following will be found a description of the ornamental part of my stove (B.B). Fig 1 is the back plate furnished with a moulding (a) around its edges a sectional view of which is represented in Fig 6. The edges of the sides and front plates are furnished or finished with a similar moulding represented by the letter (a,a) throughout all the drawings - 3, 3 and 4

is panels represented in Fig 1. the panels (3, 3) are furnished with cylindrical pieces (5, 5) placed in the centre in Demi Relief there is flakes cut of an angular form from the centre pieces (5, 5) to the edges which is provided with an offset represented at (99) panel 4 has a similar finish with the exception of the Ball 1, 1 placed in the centre in demi relief. The doors (1, 1) & panel (2) in Fig 2 together with the doors (1, 1) & f. f. in Fig 3 has a similar finish to the panel 4. in Fig 1 (1, 1) represents the Ball in Demi Relief in all the doors and the panels 2 & 4. (6, 6, 6) in Fig 2 and 1 in Fig 3 is panels at the sides and between the doors, furnished with a finish similar to those in Fig 1 represented by 3, 3. the cylindrical pieces (5, 5, 5, 5) in Demi Relief and off-set, 99, are all represented in the panels alluded to. A 'A' is the front plate above the Hearth (d, d) and A 'A' is the front plate below the hearth (d, d) seen in Fig 2. (9, 9) represents the edge of the bottom plate furnished with an Ogee moulding (10, 10) represents the feet showing their form and finish 8, 8 represents the top plate the edge of which is furnished or finished with a group of quarter Bead mouldings as the drawings represents (d, d, d) is the Hearth and hearth plate the edge of which is furnished with a moulding (c, c) and represented in a sectional view in Fig 7 b, b. represents mouldings around the edges of all the doors, the form of which is represented in a sectional view in fig 5.

What I claim as my invention or production and desire to have secured to me by Letters Patent is the Design and configuration of the ornamental stove all in combination as herein substantially specified and represented in the accompanying drawings

Witnessed
Robt: F. Adams.
